ARTICLE AND METHOD BY WHICH "BEN DAY" TONES ARE PHOTOGRAPHICALLY PRODUCED

Fayette E. Marsh and Charles H. Andersen,
Los Angeles, Calif.

Application May 8, 1934, Serial No. 724,534

6 Claims. (Cl. 95—5)

This invention relates to improvements in methods of preparing printing plates by the photo-engraving or lithographic process, with special regard to the means of introducing into the said plates shades or tones, generally known as "Ben Day" patterns.

It is well known in the engraving art, that "Ben Day" tones or shades may be introduced into the plates from which a printed image is produced by one of several methods which fall into two general classifications. By methods in the first of these classifications, the pattern is placed directly upon the plate in ink before it is etched, and by methods in the second classification the pattern is introduced into the camera copy and thereafter transferred to the plate as a component part of the image to be reproduced, by the means regularly employed in the art. The improved process, provided by this invention, falls within the latter classification and photographically produces a copy of the subject to be printed, into which copy has been introduced or added the desired tones or shades in "Ben Day" pattern. This copy containing the added shades or tones is then used as camera copy for re-production of plates by the engraver.

This invention further relates to improvements in the Method of photographically producing "Ben Day" tones, patented May 8, 1934, #1,957,790; and carries forward some of the important steps outlined therein.

This invention still further relates to improvements in the Method of photographically producing "Ben Day" tones, pending application filed July 5, 1933; Serial Number 679,012.

We have discovered in the operation of the process described in the above methods that by photographing different reflective coloring matters through a stencil in "Ben Day" or other pattern, there is produced on the camera film a negative image of the stencil, reduced or enlarged, in the areas colored, depending upon the light reflective value of the coloring matter being photographed. Neither is the process limited to opaque coloring matters only.

For example, if the stencil used contains small round openings of a mesh of 60 to an inch, which openings make up 50% of the total area of the stencil, white reflective coloring matter will register on the film in the camera a pattern of black dots which are considerably larger than the openings in the stencil and green or semi-transparent reflective coloring matter will register on the film a pattern of black dots

which are considerably smaller than the openings in the stencil.

Upon the discovery and knowledge of the foregoing facts and their utilization are based the foundation for new improvements which constitute the essence of the present invention.

Important objects are listed as follows:

First, the invention contemplates the elimination of certain steps disclosed in the parent application first referred to supra, whereby the operation is simplified and the cost of manufacture is reduced.

Second, the comparative ease by which a multiplicity of graduated tones may be produced.

Third, it provides a means whereby plates can be remade, should the plates become damaged or broken.

Fourth, it provides an article of manufacture.

Other objects, not listed, will be apparent when viewed in the light of the drawing and what is claimed; also how much of the cost of producing tones or shades on printing plates is eliminated and how the engraving art is greatly enriched by the ease and flexibility of its use, especially in the making of so-called "color plates".

With the use of the embodiment shown in the accompanying drawing, the article and method whereby "Ben Day" tones are photographically produced will now be disclosed.

The following is a brief description of the figures in the drawing:

Fig. 1 represents the master drawing.

Fig. 2 represents the transparent overlay, on which coloring materials have been layed.

Fig. 3 represents a transparent sheet on which a "Ben Day" pattern has been printed in opaque ink called a stencil.

Fig. 4 represents a master drawing on which coloring materials have been layed.

Fig. 5 represents a composite assembly of the transparent overlay shown in Fig. 2 and the stencil shown in Fig. 3, positioned so that the transparency can be photographed thru the stencil.

Fig. 6 represents a composite assembly of the master drawing shown in Fig. 4 and the stencil shown in Fig. 3, so positioned that the master drawing can be photographed thru the stencil.

Fig. 7 represents the photographic image in negative form, produced by photographing the assembly shown in Fig. 5 or the assembly shown in Fig. 9.

Fig. 8 represents the photographic image in

negative form, produced by photographing the assembly shown in Fig. 6.

Fig. 9 represents a transparent sheet containing a "Ben Day" pattern or stencil on which a figure has been painted in colors on the stencil side.

The disclosure of the article and method whereby "Ben Day" tones or shades are photographically introduced into a given subject now follows step by step.

First we provide a suitable subject to be shaded which in the present instance is termed a master drawing and represents a cube (block). Such a subject is shown in Fig. 1.

Next, we superimpose on the face of the master drawing a transparent sheet and upon said sheet lay various reflective coloring materials, having different reflective coloring values, corresponding to the areas on which different values of the "Ben Day" pattern are to subsequently appear in the photographic negative.

Pursuant to this plan we color that area white where we wish to produce on the corresponding area of the film in the camera, a dark "Ben Day" tone or shade, and that area blue-green where we wish to produce on the corresponding area of the film in the camera, a light "Ben Day" tone or shade.

Other areas, we color in intermediate tones of blue-green to white, where we wish to produce on the corresponding area of the film in the camera, intermediate "Ben Day" tones.

A similar arrangement of other reflective coloring matters having different reflective values may be utilized to produce like results and therefore can be used interchangeable.

Next we remove the overlay from the master drawing and position it before the camera for reproduction and superimpose on the overlay in that position, a stencil in "Ben Day" pattern. The assembly at this stage of the process is represented in Fig. 5. The assembly is then photographed and the negative produced is represented in Fig. 7 and constitutes the article.

It will be noticed that when the overlay is removed from the master drawing and photographed thru the stencil, the lines of the drawing are not reproduced on the photographic negative obtained, but it rather contains only the varying values of "Ben Day" patterns resulting from photographing the coloring materials previously layed upon the overlay. When and if the lines of the master drawing are to be carried into the negative, we place reflective coloring materials directly upon the surface of the master drawing as shown in Fig. 4. We then proceed as in the case of the removable overlay above described with the same result upon the photographic negative except that the lines of the drawing are thereupon shown. The assembly of master drawing and stencil is represented by Fig. 6, the negative produced by photographing the assembly is represented by Fig. 8 and constitutes the article.

This process can be effectively worked without reference to a master drawing or the use of its lines as guides for laying the coloring materials when certain types of subjects are involved. To proceed without the master drawing as shown in Fig. 1, we build up the image desired, by the application of the coloring materials directly to the surface of the stencil on its printed side in the same manner as would an artist with his brush in painting a picture of an object. This assembly is represented in Fig. 9.

We then proceed as in the case of the removable overlay above described with the same result upon the photographic negative. In the first instance, the colors are upon a transparency and the stencil is superimposed. In the latter, the colors are upon the stencil with the opaque ink pattern between them and the camera. The negative produced by photographing the assembly is represented in Fig. 7.

The negatives represented by Figs. 7 and 8 are commercial products valuable to the trade as known for printing to metal in the making of etched plates.

Although Figs. 1, 2 and 3 are not shown upon the drawing in composite assembly, were there occasion, as will from time to time occur, to produce a negative which contains the lines of the drawing as represented by Fig. 8 when the placing of coloring materials upon the surface of the drawing is damaging to it or otherwise undesirable, we would proceed as above described except that Fig. 1 would be placed beneath the assembly shown in Fig. 5, which assembly when photographed would produce the negative as represented by Fig. 8.

This invention contemplates broadly the method of photographing various reflective coloring matters, having different reflective values, through a transparency on which has been imprinted, one one of the faces thereof, a "Ben Day" pattern.

It has been disclosed, step by step, by the method hereinbefore described. Whether the various reflective coloring matters are placed on the "Ben Day" stencil or on the master drawing, is considered patentably immaterial, so long as the stencil and the coloring matter is contiguous. This would be interpreted as meaning, placing the coloring matter on the transparency against the stencil design itself, as stated supra, or placing the various reflective coloring matters on a master drawing and then placing the imprinted side of the stencil against the coloring matter and photographing the combination.

We claim:

1. The method of producing "Ben Day" tones or shading effects which consists in providing a master drawing to be toned, placing upon the surface of said drawing various reflective coloring matters, having different reflective values, said reflective coloring matters being spaced where "Ben Day" tones are to subsequently appear on a photographic negative of said drawing, superposing upon said drawing a transparency containing a "Ben Day" pattern, and photographing the combination with said transparency nearest the camera.

2. The method of producing "Ben Day" tones or shading effects which consists in providing a master drawing to be toned and a transparency containing a "Ben Day" pattern, placing upon the surface of said drawing various reflective transparent coloring matters, having different reflective values, where "Ben Day" tones are to subsequently appear on a photographic negative of said drawing, and photographing the combination in registry with the pattern side of the transparency next to the drawing with said transparency nearest the camera.

3. The method of producing "Ben Day" tones upon a photographic negative which consists in coloring the areas in a drawing with materials having different color reflective values on which tones are desired when reproduced by printing

and photographing the same thru a stencil in "Ben Day" pattern.

4. The method herein described of providing a transparency having imprinted on one side thereof a "Ben Day" pattern, applying on the printed side of said transparency various reflective coloring matters having different color reflective values constituting a master drawing and photographing said drawing and pattern as a whole, with the pattern on the camera side.

5. An article comprising a composite arrangement of master drawing forming a background, and a transparency containing a pattern in "Ben Day" through which said background is photographable, and suitable reflective coloring matters, having different reflective values, placed on the abutting faces of said background and transparency where gradations of tone of said pattern in "Ben Day" are to subsequently appear on a

photographic negative made from the photographic assembly.

6. An article comprising a composite arrangement of master drawing forming a background, and a transparency containing a pattern in "Ben Day" through which said background is photographable, and suitable reflective coloring matters, having different reflective values, placed on the abutting faces of said background and transparency where gradations of tone of said pattern in "Ben Day" are to subsequently appear on a photographic negative made from the photographic assembly, whereby when the image of the whole is reproduced the pattern in "Ben Day" will appear in varying degree in the local areas colored according to the reflective value of the coloring matter used.
